INVENTOR

K. GUMUCHIAN

UNITED STATES PATENT OFFICE.

KIRKOR GUMUCHIAN, OF NEW YORK, N. Y., ASSIGNOR TO BIGELOW HARTFORD CARPET COMPANY, A CORPORATION OF MASSACHUSETTS.

DESIGN FOR A RUG.

51,014.

Specification for Design.

Patented July 10, 1917.

Application filed May 14, 1917. Serial No. 168,612. Term of patent 7 years.

To all whom it may concern:

Be it known that I, KIRKOR GUMUCHIAN, a citizen of the United States, residing at New York, in the county of New York and State of New York, have invented a new, original, and ornamental Design for a Rug, of which the following is a specification, reference being had to the accompanying drawing, forming part thereof.

The drawing illustrates a portion of a rug, showing my new design.

I claim.

The ornamental design for a rug, substantially as shown.

KIRKOR GUMUCHIAN.

Witnesses:
